UNITED STATES PATENT OFFICE.

TOM WISEMAN LOWDEN, OF LONDON, ENGLAND, ASSIGNOR TO THE ACTON LAMP COMPANY LIMITED, OF LONDON, ENGLAND.

INCANDESCENT ELECTRIC LAMP.

1,083,331

Specification of Letters Patent.

Patented Jan. 6, 1914.

Application filed January 14, 1913. Serial No. 741,945.

To all whom it may concern:

Be it known that I, TOM WISEMAN LOWDEN, a subject of the King of Great Britain, residing at London, England, have invented certain new and useful Improvements in Incandescent Electric Lamps, of which the following is a specification.

This invention relates to improvements in incandescent electric lamps, more especially to lamps with drawn filaments, and has for its object the provision of a support for the filament of such lamps which will enable it to expand and contract without damage and also to withstand the shocks unavoidable in use and transit.

It has been proposed to support a continuous filament in a vertically disposed zig-zag and circular path by hanging it upon light metal hooks at each bend of the zig-zag, but difficulty has been experienced in that fusing of the metal occurs at the hanging points and causes breakage; local cooling at the hook will also sometimes cause breakage.

This invention consists in forming supports for the filament out of the filament itself, by looping it at the several bends and then preferably twisting such loops rope-fashion, or welding the two parts of the loop together. These looped or twisted portions are bent over both at the upper and the lower ends of the bends, and the extreme ends of the same are then secured directly to a non-conductive support by heating the glass supporting ridges, and embedding the ends of the twisted loops in the glass when heated to a plastic condition, or by attaching them by paste or enamel by any convenient method to the central stem of the lamp; this allows of eliminating the usual hooks or similar independent supports. If filaments in short lengths are used a twisted loop may be formed so as to serve as the support at one end of the central stem, the loose ends of the filament being welded to supports by any ordinary known method.

Since the current is short circuited at the contact point of the loop there will be only quite a low temperature in the loop itself whether twisted or otherwise, and probably also a somewhat reduced temperature for a slight distance along the incandescent straight lengths away from the contact point, due to the larger cross section of the loop part withdrawing the heat by conduc-

tion; this is a point of great advantage as the point of support is usually the weak point of the filament as a whole and is most subject to breakage.

The invention is applicable mainly to a continuous filament of the drawn variety but may also be used with a squirted filament having a plurality of separate sections joined together, or where possible in a continuous length.

The accompanying drawings illustrate the invention.

Figure 1 is a view of the complete lamp; Fig. 2 shows a line of filament being put into the lamp; Figs. 3, 4 and 5 show alternative forms of supporting sections before being bent over; and Fig. 6 shows the application of the invention to the ordinary hairpin filament.

The lamp bulb 1 is provided with the ordinary cap 2 and also with a central supporting rod 3 upon which the filament 10 is mounted, the leading in wires, 4, 4 being brought in through the glass 5 in the ordinary way and connected to the filament.

The filament is preferably formed of a continuous length as shown in Fig. 2, having each of the bends made with a twisted loop 6 and 7, at the top and bottom respectively, which is afterward bent over and forms the connection of the filament 10 with the ridges 8 and 9 on the lamp stem 3; the looped or twisted portions are melted into the glass ridges and thus firmly secure the filament thereto.

Rigid supports may be used in place of twisted portions at one end of the filament bends, and in the case of the ordinary hairpin filament as shown in Fig. 6, the bend 12 of the filament is advantageously looped or twisted to support that end while its free ends are supported by welded or other suitable connections of known form; such a connection is shown at 11, 11 where the wires 11 also carry the current from one filament 100 to the next.

The construction of the loops may be varied according to circumstances; Fig. 3 is the preferred form being simply the filament doubled on itself and then twisted; Fig. 4 is the twisted form when separate strands of filament are used for each section, the ends being firmly secured by the twist; Fig. 5 illustrates the looping with twist, its sides being welded together with 110

the aid of a high voltage current to strengthen the connection to the central non-conductive support.

It should be understood that the Figs. 5 to 5 illustrate the loop before being bent over to form the filament connection as shown in Figs. 1 and 2.

What I claim as my invention and desire to secure by Letters Patent is:

- 10 1. The combination, in an incandescent electric lamp, of a filament in multiple line form, a non-conductive lamp portion disposed alongside the filament, and doubled integral and contacting portions of the filament itself bent over to form its support from the said non-conductive lamp portion, substantially as set forth.
- 15 2. In an incandescent electric lamp, the combination of a non-conductive lamp portion, with a continuous filament having double contacting portions integral with itself throughout such contacting portions forming short circuited branches as supports for the said filament from the non-conductive lamp portion.
- 20 3. In an incandescent electric lamp, the combination of a non-conductive lamp portion, with a continuous filament, having twisted portions integral with itself throughout, and forming the supports for the said filament from the non-conductive portion.
- 25 4. In an incandescent electric lamp, the combination of a non-conductive lamp portion, with separate lengths of filaments having portions of their ends joined together as double contacting branches which are bent over to form supports from the non-conductive portion of the lamp.
- 30 5. In an incandescent electric lamp, the combination of a non-conductive lamp portion, with separate lengths of filaments having their ends twisted together, such twisted portions being bent over to form supports from the non-conductive portion of the lamp.
- 35 6. In an incandescent electric lamp, the combination of a non-conductive lamp portion, with separate lengths of filaments, one end of each length being joined in contact with the end of the next length and such double portions being bent over to form one support from the non-conductive portion of the lamp, and rigid supports attached to the non-conductive lamp portion securing the

other ends of the filament lengths by any known connection thereto.

7. In an incandescent electric lamp, the combination of a non-conductive lamp portion, with separate lengths of filaments one end of each length being twisted up with the end of the next length and such twisted portions being bent over to form one support from the non-conductive portion of the lamp, and rigid supports attached to the non-conductive lamp portion securing the other ends of the filament lengths by any known connection thereto.

8. In an incandescent electric lamp, the combination of a non-conductive lamp portion, with a hair pin filament having a double contacting branch bent over from the bend to the filament to form a flexible support at one end, and conductive supports for its free ends.

9. In an incandescent electric lamp, the combination of a non-conductive lamp portion, with a hair pin filament having a twisted branch bent over from the bend of the filament to form a flexible support at one end, and conductive supports for its free ends.

10. In an incandescent electric lamp, the combination of a central glass stem having upper and lower flanges thereon, with a zig-zag filament, and double integral and contacting portions of the filament itself bent over at the top and bottom of the zig-zag construction and embedded in the upper and lower flanges respectively of the central glass stem, all substantially as set forth.

11. In an incandescent electric lamp, the combination of a central glass stem having upper and lower flanges thereon, with filaments having supports formed by doubled integral and contacting portions of the filament itself embedded in one flange of the central stem, rigid supports embedded in the other flange of the said stem, and means for connecting the rigid supports with the free ends of the filaments, all substantially as described herein.

In testimony whereof I affix my signature in presence of two witnesses.

TOM WISEMAN LOWDEN.
